UNITED STATES PATENT OFFICE.

ADNAH McMURTRIE, OF NEW YORK, N. Y., ASSIGNOR TO THE THOMAS & BETTS CO., OF ELIZABETH, NEW JERSEY, A CORPORATION OF NEW JERSEY.

ADAPTER FOR CONNECTING DEVICES.

Application filed November 10, 1920. Serial No. 423,061.

To all whom it may concern:

Be it known that I, ADNAH McMURTRIE, a citizen of the United States, residing in the city, county, and State of New York, 5 have invented certain new and useful Improvements in Adapters for Connecting Devices, of which the following is a specification.

My invention relates to devices for connecting electrical conduits, cables, or the like to electric outlet boxes and the like. It 10 relates more particularly to what I may term adapters for connecting devices, by which I mean appliances which may be used in connection with connectors, to enable a connector of one size to be mounted within openings of other or different sizes in outlet boxes or the like.

There are at present a large variety of 20 connectors on the market designed to fit conduit openings of different sizes, in outlet boxes. Various different designs are made to fit a one-half inch conduit opening, for example, these connectors being of different 25 sizes and shapes to permit the attachment, at various angles, of different sizes of conduits and cables to an outlet box or other appliance. Various other designs of connector are made for use in connection with 30 three-quarter inch openings in outlet boxes while others are designed for use in connection with one inch openings in outlet boxes. The aim of my invention is to provide attachments whereby any design of 35 connector intended for use with a half-inch opening, for example, may readily be used in connection with openings of a larger size such as three quarter inch or one inch. Accordingly, by the use of my invention, the 40 variety of connectors which must be manufactured and kept in stock will be greatly reduced.

I accomplish this purpose, very simply 45 and efficiently, by the provision of bushings and also preferably of washers, which may be mounted on the neck of a connector. Each bushing is provided with a head and with a shank of less diameter than the head. The shank has an external diameter of a 50 size suitable to seat within a desired opening in an outlet box wall. The connector, of a size smaller than that of a particular opening, may be secured in position by utilizing an abutment preferably by mounting 55 a washer, on the neck of the connector in

position to engage one surface of the box wall surrounding the opening, while the bushing is mounted on the connector neck in position to insert the shank of the bushing through the opening and to cause the head 60 of the bushing to engage the opposite surface of the box wall.

In order that my invention may be more clearly understood attention is hereby directed to the accompanying drawings forming 65 part of this application and illustrating certain embodiments of my invention. In the drawings, Fig. 1 represents a vertical section showing one form of my invention, mounted in position, an electric conduit being shown therein, in side elevation; Fig. 2 is a view partly in side elevation and partly in section, of the various parts of the device shown in Fig. 1, separated for clarity; Fig. 3 is a view partly in side elevation and partly in section of another form 70 of device embodying my invention; Fig. 4 is a front elevation of the device shown in Fig. 3 and Fig. 5 is a vertical section through a modified form of device embodying 75 my invention, a portion of the electric conduit being shown in side elevation.

Referring to the drawings the connector shown in Figs. 1 and 2 is of a well known form embodying a neck 1 provided with external screw-threads 2. At the rear end of the screw-threaded neck a peripheral flange 3, of greater diameter than the threaded neck, is provided, a clamping ring 4 being provided at the rear end of the connector. This ring is shown as having a pair 80 of up-turned ends 5, 5 through openings in which a screw 6 is extended. An electrical conduit or cable 7 passed through the connector may be clamped in position by tightening the screw 6, the ring 4 having one side-portion 4' which is separated from the body of the connector and is free to be moved toward and away from the other side of the ring by means of the screw, in the 85 usual manner.

The connector is adapted to be secured to an outlet box having an opening of one-half inch diameter, for example, within which opening the neck 2 is designed to fit. 105 When the connector is to be used with an outlet box having an opening of three-quarters inch diameter, for example, in its wall represented at 8, a bushing 9 of suitable size is used. This bushing is provided 110

with a head 10 and a shank 11 of less diameter than the head. The bushing may be provided with internal screw-threads shown at 12, adapted to engage with the threads 2 on neck 1. The head 10 may be of a form suitable for easy manipulation by the thumb and finger of the person mounting the device.

The shank 11 is of a suitable diameter so that it may be slipped through the opening in the wall 8. If the opening is of three-quarters inch diameter, for example, the shank 11 will be of an external diameter slightly less than three-quarters of an inch. And similarly, if the connector is to be used with a larger opening such as one of one inch diameter, a different bushing will be used having a shank 11 the external diameter of which is slightly less than one inch.

The head 10 of the bushing being adapted to engage against one surface, such as the inner surface, of the wall 8, means are provided for engaging the opposite or outer surface of the wall, about the opening. If the connecting device itself is provided with no suitable abutment means for this purpose, a separate abutment means, in the nature of a washer, may be provided. I have illustrated such a washer at 13, this washer having a radially extending portion 14 which is adapted to be slipped over the neck 2 into engagement with shoulder 3. The washer also has a peripheral flange 15 of suitable diameter extending about the opening in the wall 8 so that the end of flange 15 may bear against the adjacent surface of wall 8 surrounding the opening therethrough.

The washer may be loosely slipped over the neck of the connector, as shown, so that it will engage against the shoulder 3, or it may be secured to the connector by screwing the same thereon or otherwise fastening it in place on the connector, it not being deemed necessary to illustrate the various methods in which the washer may be so mounted. When, as above suggested, the arrangement is such that the head of the bushing engages the inner surface of the box-wall, the washer will be so located as to engage the outer surface thereof. It is apparent, however, that this relative arrangement may be reversed.

In the embodiment of the invention shown in Figs. 1 and 2, it will be noted that the shank 11 is of a length greater than the thickness of the wall 8, so that it extends some distance through the opening. In such a case the flange 15 of the washer must, of course, be of an internal diameter sufficient to enable it to extend around the shank of the bushing, so that the end of the flange 15 may bear against the adjacent surface of wall 8.

In Figs. 3 and 4 I have illustrated the use

of the same type of adapter in connection with a connector 16, which may be used when the conduit or cable has to make an angle in approaching the opening in wall 8. In such a case the neck 1 of the connector is joined to an elbow portion which is completed, in the example shown, by a cover plate 17 which carries a clamping strip 18, adapted for use in connection with the opposite clamping portion 18' of the body of the connector. The bushing 9 and the washer 13, shown in this example, may be the same as the bushing and washer shown in the form of device illustrated in Figs. 1 and 2.

The modification shown in Fig. 5 differs from the form shown in Figs. 1 and 2 because of the fact that the bushing 9', shown in Fig. 5, is not provided with internal screw-threads. In the form shown in Fig. 5 the bushing is provided with a threaded opening through the head thereof through which is extended a screw 19 which may be screwed into binding engagement with the thread 2 on the neck 1 of the connector, when the bushing has been adjusted in position.

This figure also illustrates the use of a bushing having a shank 11' which is of less length than the thickness of wall 8. In such a case the washer 13' need have no peripheral flange such as that shown in the other figures. Washer 13' may be simply a flat washer, as shown slipped over the threads of neck 1 into engagement with shoulder 3, or otherwise secured in position on the connector, the external diameter of the washer being greater than that of the opening through wall 8, so that the outer portion of the forward face of the washer will bear against the outer surface of wall 8 when the parts are adjusted into position.

It will be understood that my invention is not limited strictly to the details of construction described but is as broad as is indicated by the accompanying claims.

What I claim is:

1. In connecting devices, in combination, a member to be secured in an opening in a wall, a bushing adapted to receive said member and having a reduced portion adapted to fit within said wall opening and having another portion adapted to abut against one side of the wall at the opening, an abutment element on said member and abutting against the other side of said wall, said abutment element being recessed to permit said reduced portion of the bushing to extend through said opening, and means whereby said bushing may be secured adjustably on said member.

2. In connecting devices, the combination of a connector having a neck and a peripheral shoulder, a washer mounted directly upon said neck and adapted to bear against said shoulder, and a bushing mounted directly upon said neck and having a head and

a shank of less diameter than that of said head, said shank being adapted to seat within an opening in a wall with said head engaging one side of said wall about the opening, said 5 washer having a peripheral flange of an internal diameter greater than the external diameter of said shank, whereby the end of said flange may bear against the other side of said wall about the opening, and means 10 for securing said bushing upon said neck in adjusted position.

3. In connecting devices, the combination with a connector having a neck, of a washer and a bushing, both mounted directly on said 15 neck, said bushing having a radially extend-

ing head and a reduced shank extending at right angles to said head from the inner edge thereof, and said washer having a radial portion and a portion extending at right angles to said radial portion at the outer 20 edge thereof and radially overlapping said shank, and means for adjusting said washer and bushing on said neck relatively to each other.

This specification signed and witnessed 25 this 4th day of November, 1920.

ADNAH McMURTRIE.
